UNITED STATES PATENT OFFICE.

JOHN MORRIS GARFIELD, OF GALVESTON, TEXAS.

VENTILATING APPARATUS.

SPECIFICATION forming part of Letters Patent No. 349,491, dated September 21, 1886.

Application filed November 21, 1885. Serial No. 183,571. (No model.)

To all whom it may concern:

Be it known that I, JOHN MORRIS GARFIELD, a citizen of the United States, residing at Galveston, in the county of Galveston and State 5 of Texas, have invented a certain new and useful Improvement in Ventilators; and I do hereby declare that the following is a full, clear, and exact description of the same.

This invention is designed for ventilating 10 rooms, ships, &c.; and it consists in the construction, novel arrangement, and adaptation of devices, as will be hereinafter more fully set forth and claimed.

In the accompanying drawings, Figure 1 15 is a view of a section of a room showing my improved ventilation apparatus in an operative position. Fig. 2 is a plan view of the fan and its casing. Fig. 3 is a plan view of the operating gear. Fig. 4 is a side view of the 20 same, and Fig. 5 is a view of the weight.

Referring by letter to the said drawings, A indicates a portion of a room in which B is the ceiling, and C the upper floor.

Above the center of the room and to the 25 ceiling thereof I arrange a fan-casing, D, which is open on its under side and communicates at its upper side with air-ducts G, leading therefrom and between the floor and ceiling, as shown, to the outside of the building, whereby 30 fresh and pure air may be conducted to a room and discharged therein by means of a fan, as will be presently explained.

Above the fan-casing and between the ceiling and floor is arranged on suitable plates a 35 system of gearing, E, which may be similar to an ordinary clock-gear—in the present instance there being a large number of gearing employed, so as to avoid frequent winding of the weight. In the center of the nest of gearing is a pinion, a, which receives its motion therefrom, and from this pinion through the ceiling extends a fixed shaft, b, which is secured at its lower end to the fan-blades. This fan is of substantially S form in outline, and 40 so arranged as to draw the fresh air from the ducts G and forcibly discharge the same into a room or other compartment. One of the gears F is provided with a fixed drum, H,

around which passes an endless chain or rope, I, which imparts motion to the gearing, from 50 whence it is communicated to the fan-shaft and fan. This rope I passes from the drum H in a horizontal position between the ceiling and floor to and over a pulley, J, which is journaled at the one edge thereof, and from this 55 pulley to an upper pulley, K, journaled above the pulley J and between the walls of the building, over a drum, L, which is also journaled between the walls and at a convenient point to be reached by a person in the room, and thence 60 over a pulley, M, which may be beneath the lower floor or in the cellar of a building, the rope being carried back over the same course, so as to be made endless. To this endless rope, 65 between the vertical walls, is secured a weight, N, which is designed to operate the gearing and fan, the gearing being so arranged, as before described, that the fan may run for any desired time after the weight has been wound up.

The drum L is provided with a crank, P, for 70 turning the same, which crank may be removable.

While I have described my invention as being applied to a room of a building, it is obvious that the same may be arranged on ships 75 or other places, and a continuous current of fresh air drawn in for ventilation.

Having described the invention, what I claim, is—

1. The combination, with a fan-casing, constructed and arranged as described, of the fan arranged therein, the gearing placed above the fan, the air-ducts leading to the fan-chamber, the endless weighted chain or cord, and drums and pulleys arranged substantially as 80 specified.

2. In a ventilating apparatus, a fan-chamber having an open bottom secured to a ceiling and communicating with air-ducts passing between the floor and ceiling of a building, the 85 fan in the said casing, and means for rotating the said fan, substantially as specified.

JOHN MORRIS GARFIELD.
